US0D1106334S

(12) United States Design Patent (10) Patent No.: US D1,106,334 S
(45) Date of Patent: * Dec. 16, 2025

(54) GAMING MACHINE

(71) Applicant: Everi Games Inc., Austin, TX (US)

(72) Inventors: Travis Bussey, Austin, TX (US);
Daniel Gibson, Austin, TX (US);
Courtney Bell, Austin, TX (US);
Steven Speer, Austin, TX (US); Craig Gallagher, Austin, TX (US); Ryan Greene, Austin, TX (US); Nathan Careless, Cedar Park, TX (US)

(73) Assignee: Everi Games, Inc., Austin, TX (US)

() Term: 15 Years

(21) Appl. No.: 29/855,957

(22) Filed: Oct. 9, 2022

(51) LOC (15) Cl. 21-01

(52) U.S. Cl.

(57) CLAIM

The ornamental design for a gaming machine as shown and described.

DESCRIPTION

FIG. 1 is a left perspective view of a gaming machine showing the new design.

FIG. 2 is a front elevation view thereof.

FIG. 3 is a rear elevation view thereof.

FIG. 4 is a right side elevation view thereof.

FIG. 5 is a left side view thereof.

FIG. 6 is a top view thereof; and,

FIG. 7 is a bottom view thereof.

The broken lines immediately adjacent to the shaded areas depict the bounds of the claimed design, while all other broken lines are directed to environment. The broken lines form no part of the claimed design.

1 Claim, 6 Drawing Sheets
